FIG. 6.

FIG. 7.

6 INVENTOR

EDWARD F. HONIUS,

By *Doulinin* & *Doulinin*,

ATTORNEYS

UNITED STATES PATENT OFFICE.

EDWARD F. HONIUS, OF NORTH MANCHESTER, INDIANA.

TOOL.

Application filed December 29, 1924. Serial No. 758,620.

This invention relates to tools for removing sleeves from housings, such as the rear system axle housing of Fords.

The object of the invention is to provide a tool which will enable the user to quickly and easily perform the removal of sleeves from housings, said tool being economical to manufacture, and readily packed and stored. To this end I have provided a sleeve 10 pulling tool having a member adapted to be inserted in the sleeve to be removed and a lifting bar cooperating with said member.

In the accompanying drawings:—

Fig. 1 is a perspective view showing the tool in position ready to pull a sleeve from a housing removed from a car;

Fig. 2 is a similar view showing the position of the tool and sleeve after the sleeve has been pulled out of its housing, and the 20 relation of the plunger to this sleeve;

Fig. 3 is a sectional view of the pulling member of the tool with its cooperating lifting member in elevation;

Fig. 4 is a sectional view taken on the line 25 4—4 of Figure 5 and showing the spring plunger;

Fig. 5 is a sectional view taken through the lower part of the pulling member shown in Fig. 3 illustrating the means for limiting 30 the movement of the plunger;

Fig. 6 is a section on the line 6—6 of Fig. 7 illustrating a modification of my pulling tool; and

Fig. 7 is a section on the line 7—7 of 35 Fig. 6, and looking in the direction of the arrows.

In these drawings, 1 designates a pulling or lifting member which may be formed in any suitable manner. In the present instance I have shown it as made of tubing, having a plurality of apertures 2, for the purpose hereinafter set forth. Rigidly secured in the lifting member 1 is a casing 3 having a slot 4, said casing being screw-threaded on its inner surface for a short distance, as shown at 5. In the drawings the casing 3 is shown near the bottom of the member 1, but it may be located at any desired place to adapt the tool for use in various constructions. Mounted within said casing 3 is a retaining plug 6 carrying a spring 7 attached to a plunger 8. The plunger 8 is provided with a stud or tongue 8^a adapted to travel in said slot 4 and limit the movement of the plunger in its relation to the

member 1. A lifting bar 9 having a fulcrum 10 pivoted at 11 completes the tool. The lifting bar is shown in the drawing as having a rounded head at one end, adapted to enter the apertures in the member 1. It will be noted that a series of apertures similar to the apertures 2 may be located in the member 1, opposite the apertures 2 so that the lifting bar may be used from different positions.

In the drawings I have shown one manner of using the tool in removing the sleeve from the rear axle housing of a Ford car when the housing has been removed, but it will be understood that it may be used in other ways. As shown, the housing 12 is up-ended, with the outside bearing sleeve 13 extending upwardly. With the housing in this position, the member 1 of the pulling tool is inserted in the sleeve 13 by pushing 75 the spring plunger 8 back, flush with the lifting member. The lifting member is pushed down into the sleeve as far as it will go and is then turned around until the plunger 8 snaps into the grease cup hole in 80 the sleeve 13. The bar 9 is then inserted in the uppermost aperture in the member 1 and the fulcrum 10 rested on the housing. As pressure is applied to the bar 9, the member 1 is raised, bringing with it the roller bearing sleeve by means of the plunger 8. The lifting bar 9 may be moved from the topmost aperture 2 to the next lower aperture and so on until the sleeve is pulled completely out of the housing.

In the form of the device shown in Figs. 6 and 7, I have shown the same provided with means for adapting it for use in pulling sleeves from housings when the housing is not removed from the car in addition to the 95 means for pulling sleeves from housings when removed from the car, thereby providing a tool having a dual function. To this end the member 14 is provided with two series of apertures 15 extending substantially the entire length of the same so that there will be apertures adjacent the plungers 16 and 25 adapted to receive the head of the lifting bar 9 according to whether the housing has been removed or not removed. The 100 two series of apertures are provided to adapt the tool for use on either side of the car and enable the operator to place the bar 9 so that it may be easily operated from different positions. Near one end of the 110

member 14 I provide a plunger construction identical with the construction shown in Figs. 1 to 5 for use when the housing has been removed, in which 16 indicates the 5 plunger, 17 the casing therefor, 18 the spring, 19 the plug and 20 the opening in said casing to receive the pin 21 and limit the movement of the plunger. Near the opposite end of the member 14 I provide a 13 plunger construction for use when the housing is not removed, comprising an aperture 22 adapted to receive a projecting member or plunger 23 having a shank portion 24 the end of which is adapted to extend about a 17 screw 25 or other means secured in the member 14. The plunger 23 is held in place by a spring 26 secured to the member 14 by said screw 25 and a second screw 27. Apertures 28 and 29 in the member 14 opposite the screws 26 and 27 permit access to the heads 30 of said screws for adjustment purposes.

It will be seen that the construction for the plunger 16 is preferable in that it is stronger but is only capable of use when the 25 housing has been removed from the car, while the plunger construction 23 will permit the member 14 to be slipped over the axle and inserted in the sleeve until said plunger 23 snaps into the grease cup and 30 thus enable the operator to pull out the sleeve by the bar 9 without removing the housing from the car. In this way I have provided in a single tool means for performing the same operation under different 35 conditions and this is important in that it enables the operator to accomplish with one tool what heretofore required two tools.

From the foregoing description it will be 40 seen that with my improved tool, sleeves may be removed from the housings more

quickly and easily; and also that it may be cheaply manufactured.

While I have shown and described certain embodiments of my invention, I do not wish to be understood as limiting myself to the 45 details of construction, for obvious modifications will appear to one skilled in the art.

Having thus fully described my invention, what I claim as new and desire to secure by Letters Patent is:—

1. In a pulling tool of the character described, a member having a plurality of openings, means mounted in said member adapted to be held flush therewith or extended beyond it, whereby said member may be inserted in and locked to a device, and means for successively engaging the openings in said member to exert a pulling or lifting action on said member and the device locked thereto.

2. In a device of the character described, the combination with a pulling member having a plurality of apertures and a spring-pressed plunger near one end thereof, a housing for said plunger, and means for limiting the movement of said plunger, of a lifting bar having one end adapted to enter successively the apertures in said pulling member.

3. In a device of the character described the combination with a pulling member having a plurality of apertures and a spring-pressed plunger near one end thereof, and means for limiting the movement of said plunger, of a lifting bar having one end adapted to enter successively the apertures in said pulling member.

In testimony whereof I affix my signature.

EDWARD F. HONIUS.
